UNITED STATES PATENT OFFICE.

JOHN W. THOMAS, OF CHICAGO, ILLINOIS, ASSIGNOR TO THE THOMAS RAILWAY TRACK APPLIANCE COMPANY, A CORPORATION OF KANSAS.

RAILWAY-TRACK APPLIANCE.

1,227,859.

Specification of Letters Patent.

Patented May 29, 1917.

Application filed November 19, 1915. Serial No. 62,390.

To all whom it may concern:

Be it known that I, JOHN W. THOMAS, a citizen of the United States, residing at Chicago, in the county of Cook and State of Illinois, have invented certain new and useful Improvements in Railway-Track Appliances, of which the following is a specification.

My invention relates to improvements in railway track appliances, and one object of the invention is to provide a device of this character whereby a rail may be reliably secured to an underlying cross-tie without the use of spikes, screws, etc.

15 A further object is to secure the rail to the tie in such manner that said rail cannot tip over, even when subjected to the enormous pressure exerted by a rapidly moving train in rounding a curve.

20 Other objects of the invention will hereinafter appear, and in order that said invention may be fully understood, reference will now be made to the accompanying drawings, in which:

25 Figure 1 is a broken plan view of a rail and the underlying cross-tie bound together with my appliance.

Fig. 2 is a cross section on line II—II of Fig. 1.

30 Fig. 3 is a section on line III—III of Fig. 1.

Fig. 4 is a detail of a yoke constituting a part of the invention.

Fig. 5 is a section, reduced, on line V—V of Fig. 3.

Fig. 6 is a broken section on line VI—VI of Fig. 1.

Fig. 7 is a detail of a tapered member constituting a part of the invention.

40 Fig. 8 is a detail of a tapered member which coacts with the tapered member disclosed by Fig. 7.

Fig. 9 is a modified form of the invention.

Fig. 10 is a broken cross section on line X—X of Fig. 9.

Fig. 11 is a section on line XI—XI of Fig. 9.

A designates a rail and B a cross-tie underlying said rail. 1 designates the tie-plate member of my device, which is interposed between the rail A and the cross-tie B. Said tie-plate member has two depending sleeves 2 and two depending studs 3, which latter enter recesses b bored into the cross-tie to give the proper gage in laying the rails and

to assist in preventing the tie-plate member from slipping upon said cross-tie. Water is prevented from seeping between the tie-plate member 1 and the cross-tie B, and entering the recesses b, by ribs 1^a, which also reinforce said tie-plate member 1.

The longitudinal sides of the tie-plate member 1 have flanges 4 and 5, the former of which is adapted to snugly embrace the adjacent rail base flange C, while the latter is spaced from the adjacent rail base flange as disclosed by Fig. 2, to receive a tapered member 6, which rests upon the tie-plate member 1 and overlaps the adjacent rail base flange C. One end of the tapered member 6 has a longitudinal extension 7 with a ballway 8, having an inclined bottom 9 communicating at its lower end with a recess 10 intermediate the ends of the tapered member 6.

11 designates another tapered member adapted to coact with the tapered member 6 in securing the rail A upon the tie-plate member 1. Said tapered member 11, like the tapered member 6, fits between the flange 5 and the adjacent side of the rail base flange C over which it laps. The tapered member 11 has an opening 12 to receive the extension 7 of the tapered member 6, and is provided at the underside of its upper wall 85 with a ballway 13 adapted to register with the ballway 8. The top 14 of the ballway 13 inclines in the same direction as the ballway 8, but has a greater pitch than the latter to check the downward movement of the ball 15, whereby the two tapered members are locked together. The upper end of the ballway 13 communicates with a recess 16, in which the ball 15 may be held to keep it out of contact with the tapered member 6 by a pin introduced through holes 17 in opposite walls of the ballway 9.

As disclosed by Fig. 1, the tapered members 6 and 11 have bevel sides 18 and 19, respectively, fitting against a corresponding 100 interior wall 20 of the flange 5. The wall 20 is beveled in opposite directions from a point about midway between its ends, so that the closer the tapered members 6 and 11 are forced toward each other the tighter 105 they engage said wall and the adjacent rail base flange, and cause the flange 4 to firmly engage its side of the rail.

21 designates an inverted yoke which extends around the bottom and two sides of 110

the cross-tie B and is removably secured in the sleeves 2 by balls 22, interposed between the sides of the yoke arms 23 and the adjacent downwardly tapering walls 24 of the sleeves 2. The balls 22 are graduated in size to fit the tapered walls 24 (Fig. 3), so that each will do its share of work in holding the yoke arms 23 in their respective sleeves. The two uppermost balls in each sleeve 2, 10 are firmly held down against the interior of the walls 24 and the adjacent side of the yoke arms 23, by coil springs 25.

In practice, the tie-plate member 1 is first applied to the cross-tie B and secured thereon by the yoke 21, the arms 23 of which are inserted in the sleeves 2. As the yoke is pushed into the sleeves the balls 22 allow the arms 23 to freely enter, but any attempt to withdraw the yoke is immediately checked 20 by the balls 22 frictionally and firmly engaging the arms 23 and the tapered sides 24 of the sleeves. Should the cross-tie B rot or break and have to be replaced by another, it is turned upside down to allow the balls 22 25 to roll down and release the yoke 21, so that the same can be removed from the sleeves 2.

After the tie-plate member 1 has been secured to the cross-tie B, as above-described, the rail A is firmly secured upon said tie-plate member by driving the tapered members 6 and 11 into position between the flange 5 and said rail, where they are frictionally and reliably held by the ball 15. In order to remove the rail from the tie-plate member 1, a pin is inserted in the recess 10 to push the ball 15 upward into the recess 16, after which the tapered members 6 and 11 can be slid out in opposite directions from beneath the flange 5.

40 In the modified form disclosed by Figs. 9 to 11, inclusive, the construction and application are similar to the preferred form, except that I substitute a screw 15^a for the ball 15 for the purpose of locking the tapered members 6 and 11 in proper position to each other and in proper relation to the flange 5 and the underlying rail base flange. Similar letters with exponents have been applied to the parts of the modified form corresponding to the similar parts of the preferred form, and hence further description of said modified form is deemed unnecessary.

Having thus described my invention, what I claim and desire to secure by Letters Patent, is:

1. In an appliance of the character described, a tie-plate member adapted to be interposed between a rail and a cross-tie, a yoke adapted to extend beneath the cross-tie and upward at opposite sides thereof and engage said tie-plate member, and frictional means for securing said yoke to the tie-plate member.

2. In an appliance of the character described, a tie-plate member adapted to be

interposed between a rail and a cross-tie, sleeves integral with and depending from said tie-plate member and spaced apart to admit the cross-tie, means extending beneath said cross-tie and adapted to enter said sleeves, and devices for securing said means in the sleeves. 70

3. In an appliance of the character described, a tie-plate member adapted to be interposed between a rail and a cross-tie, sleeves depending from said tie-plate member and spaced apart to admit the cross-tie, said sleeves having tapered walls, a yoke adapted to extend beneath the cross-tie and enter said sleeves, and means adapted to engage said yoke and the tapered walls of the sleeves to secure said yoke therein. 75 80

4. In an appliance of the character described, a tie-plate member adapted to be interposed between a rail and a cross-tie, sleeves depending from said tie-plate member and spaced apart to admit said cross-tie, a yoke adapted to extend beneath the cross-tie and enter said sleeves, and balls for locking said yoke within the sleeves. 90

5. In an appliance of the character described, a tie-plate member adapted to be interposed between a rail and a cross-tie, studs depending from said tie-plate member and adapted to enter recesses in the cross-tie, sleeves depending from said tie-plate member and spaced apart to admit said cross-tie, a yoke adapted to extend beneath the cross-tie and enter said sleeves, balls for locking the yoke within said sleeves, and 100 coil springs bearing against a number of said balls to hold them in engagement with the yoke and the sleeves.

6. In an appliance of the character described, a tie plate member adapted to be interposed between a rail and a cross-tie, means for securing the rail upon said tie-plate member, sleeves depending from said tie-plate member and spaced apart to admit the cross-tie, a yoke adapted to extend beneath the cross-tie and enter said sleeves, and means for securing said yoke to the sleeves. 105 110

7. In an appliance of the character described, a tie-plate member adapted to be interposed between a rail and a cross-tie, a flange at one side of said cross-tie member adapted to snugly embrace one of the rail base flanges, a flange at the opposite side of the tie-plate member spaced from the adjacent rail base flange, two tapered members adapted to be inserted in said space and engage each other and overlap the adjacent rail base flange, and frictional means to secure said tapered members in engagement with each other. 115 120 125

8. In an appliance of the character described, a tie-plate member adapted to be interposed between a rail and a cross-tie, a flange at one side of said tie-plate member 130

adapted to snugly embrace one of the rail base flanges, a flange at the opposite side of the tie-plate member spaced from the adjacent rail base flange, two tapered members 5 adapted to be inserted in said space and engage each other and overlap the adjacent rail base flange, and a ball to lock said tapered members together.

9. In an appliance of the character described, a tie-plate member adapted to be interposed between a rail and a cross tie, a flange at one side of said tie-plate member adapted to snugly embrace one of the rail base flanges, a flange at the opposite side of 10 the tie-plate member spaced from the adjacent rail base flange, two tapered members 15

adapted to be inserted in said space and engage each other and overlap the adjacent rail base flange, one of said tapered members having a ball receiving recess, a ball adapted 20 when in operative position to lock said tapered members together and when in inoperative position to rest in the ball receiving recess, and means for holding said ball in the receiving recess.

25 In testimony whereof I affix my signature in the presence of two witnesses.

JOHN W. THOMAS.
